UNITED STATES PATENT OFFICE.

JOHN J. WATERS, OF BROOKLYN, NEW YORK.

DESIGN FOR A BROAD KNIFE.

56,574.

Specification for Design.

Patented Nov. 9, 1920.

Application filed March 10, 1919. Serial No. 281,882. Term of patent 14 years.

To all whom it may concern:

Be it known that I, JOHN J. WATERS, a citizen of the United States, and residing at the city of New York, borough of Brooklyn, in the county of Kings and State of New York, have invented a new, original, and ornamental Design for a Broad Knife, of which the following is a specification, reference being had to the accompanying drawings, forming part thereof.

Figure 1 is a front elevation; and Fig. 2 is an edge view of a broad knife showing my new design.

I claim:

The ornamental design for a broad knife, as shown.

JOHN J. WATERS.
